UNITED STATES PATENT OFFICE

2,673,010

PRESSURE TANK

James R. Barrow, Columbiana, Ohio

Application July 14, 1950, Serial No. 173,898

1 Claim. (Cl. 222—182)

1

This invention relates to a container and more particularly to a container for holding corrosive fluids or the like.

The primary object of the invention is to facilitate the shipping and handling of fluids under pressure and more particularly fluids of a corrosive nature which are likely to injure or destroy the material from which the container is made.

Another object is to protect against such injury the container and at the same time to avoid contamination of the contents thereof through contact with the main body portion of the container.

Among its features the invention embodies a container of ferrous metal, such as steel having a heavy coating of nickel or other corrosive resistant substance on the interior thereof, which coating is of a thickness at least equal to one-fourth of the thickness of the metal from which the container is constructed.

Other features employ composite welds in joining the parts of the container together so that the portions of the welds which contact the contents of the container will be formed of the corrosive resistance substance.

Still other features include equipping the container at one end with a valve housing or chamber which is disposed within the confines of the container, and a removable cover closing the open end of the valve chamber effectively to protect the valves in said chamber from damage or being tampered with.

In the drawings:

Figure 1 is a fragmentary side view of a container embodying the features of this invention, certain portions thereof being shown in section more clearly to illustrate certain details of construction.

Figure 2 is an end view of the container.

Figure 3 is a sectional view taken substantially along the line 3—3 of Figure 1.

Figure 4 is an enlarged detailed view of the locking boss by which the cover plate of the container is held in place.

Figure 5 is a fragmentary side view of a modified form of container, certain portions thereof being shown in section more clearly to illustrate certain details of construction.

Figure 6 is an end view of the container illustrated in Figure 5, and

Figure 7 is an enlarged detailed view of the locking means for the cover of the modified form of container.

Referring to the drawings in detail this im-

2

proved container designated generally 10 comprises a hollow cylindrical body 12 which is preferably formed of ferrous metal such as steel. This body is relatively thin and is equipped on its inner side with a layer or coating of nickel or other corrosive resistant material 14 which is of a thickness at least equal to one-fourth of the thickness of the body 12. Carried at one end of the body 12 is a head 16 of steel or like ferrous metal which is preferably of considerably greater thickness than the thickness of the body 12 and carries on its inner surface a coating 18 of corrosive resistant substance such as nickel which is of a thickness substantially equal to the thickness of the coating 14 on the body 12. The head 16 is concavo-convex in form and its convex side is disposed outwardly. The junction of the body 12 with the head 16 is formed by a weld 20 such as is commonly employed in joining ferrous metals together, and joining the lining or coatings 14 and 18 is a weld 22 of nickel or other corrosive resistant metal.

Carried at the end of the tubular body 12 remote from the head 16 is a concavo-convex head 24 of a thickness substantially equal to the head 16 and carried on the concave side of the head 24 is a lining or coating 26 of corrosive resistant substance such as nickel which is of a thickness substantially equal to the thickness of the coating 14 on the body 12. Like the junction of the head 16 with the body 12, the junction of the head 24 with the body 12 is effected by a conventional weld 28 such as is commonly employed in joining ferrous metals, and a weld 30 of corrosive resistant substance joins the linings 14 and 26 so as to form a complete corrosion resistant lining for the container. Formed axially in the head 24 is a relatively large opening 32 for the reception of a relatively thin concavo-convex closing head to be more fully hereinafter described. The closing head designated generally 34 comprises a concavo-convex end member 36 provided with an annular flange 38 which fits in the opening 32 as will be readily understood upon reference to Figure 1. The concavo-convex body 36 and the flange 38 thereof are formed of a ferrous metal such as steel and is of a thickness substantially equal to the thickness of the body 12 previously referred to. A layer or coating of lining material 40, such as nickel is carried on the convex side of the body 36 and extends around the periphery of the flange 38 to form a complete protective coating for the body 36. This coating 40 is of a thickness substantially equal to the thickness of the

coating 14, and the flange 38 is passed through the opening 32 and is joined to the head 24 by a conventional weld 42 while the coatings 26 and 40 are joined by an annular weld 44 of nickel or other material which will resist corrosion. The body 36 and the coating 40 thereon are formed with aligning openings 46 in which is received the tubular shank 48 of a nipple 50 which is preferably formed of nickel or other corrosion resisting material and carries intermediate its ends an annular flange 52 forming a shoulder 54 which bears against the coating 40 and is welded thereto as at 56 by a weld of corrosion resisting material, such as nickel. Welded as at 58 to each nipple 50 is an eduction pipe 60 having its end 61 disposed adjacent the body 12 in the immediate vicinity of the weld 30 which joins the lining 14 with the lining 26. These pipes 60 are also formed of a corrosion resisting material such as nickel so as to avoid contamination of the contents of the container during storage and transportation therein. The portions of the members 49 of the nipples 50 which extend through the openings 46 are joined to the body 36 by conventional welds 62, and threaded into the cylindrical extensions 48 are valves 64 which are housed within the valve chamber 66 formed by the head 34 within the confines of the container.

Carried by the flange 38 on the head 34 are peripherally spaced inwardly extending lugs 68 which are diametrically opposed and form stops against which the peripheral edge of a concavo-convex cover plate 70 engages. Carried by the flange 38 midway between the lug 68 is an inwardly extending lug 72 and fixed to the inner side of the cover plate 70 is a hook shaped retainer 74 which is adapted to engage behind the lug 72 to aid in holding the plate 70 against the lugs 68. An angularly extending inwardly projecting lug 80 is carried by the flange 38 diametrically opposite the lug 72 and is formed with an internally screw threaded opening 82 for the reception of a cap screw 84 which projects through an opening 86 formed adjacent the edge of the plate 70 diametrically opposite the hook shaped retainer 74. Drain openings 88 are formed at spaced points in the cover 70 for draining moisture which may result from condensation within the chamber 66.

In the modified form of the invention illustrated in Figure 5, the container designated generally 90 comprises a tubular body 92 to opposite ends of which are welded heads to form a completely closed container. The head 94 is joined to the body 90 by a conventional weld 96 and is formed with an axial opening 98 in which a relatively thin head 100 is supported by a conventional weld 102. It is to be noted that the head 94 is of considerably greater thickness than the body 92 and that the head 100 is of a thickness substantially equal to the thickness of the body 92. As illustrated, the head 100 is substantially concavo-convex in form and is provided at its periphery with an annular flange 104 which fits within the opening 98. Formed in the head adjacent the longitudinal axis of the container are spaced internally screw threaded openings 106 in which valves 108 are threaded. Welded as at 110 to the head 100 and in surrounding relation with the openings 106 are nipples 112 which project into the container and support at their inner ends eduction pipes 114 which communicate with the interior of the nipples and are welded to said nipples as at 116.

The ends 118 of the eduction pipes 114 are turned outwardly toward the body 92 and their ends 118 are disposed adjacent the body 92 in the immediate vicinity of the weld 96.

Carried by the flange 104 and extending into the valve chamber 120 formed within the head 100 are circumferentially spaced lugs 122 each of which is provided with a relatively narrow overhanging lip 124 for engagement with a flange 126 carried at the periphery of a cover plate 128 which forms an end closure for the valve chamber 120. The flange 126 is provided with peripherally spaced notches 130 of a width sufficient to receive the overhanging lips 124 of the lugs 122. Carried by the flange 104 of the body 100 and extending inwardly of the chamber 120 between the lugs 122 is a lug 132 having an overhanging lip 134 which corresponds to the lips 124 previously described except that it is formed with an internally screw threaded opening 136 for the reception of the threaded shank of a cap screw 138 which when the cover 128 is in position in closing relation with the valve chamber 120 engages the flange 126 to effectively hold the cover in place. Like the cover 70 previously described, the cover 128 is formed with drain openings 140 through which moisture may escape from the interior of the chamber 120.

In use when it is desired to ship or store corrosive substances, the container illustrated in Figures 1 through 4 inclusive is employed and it will be obvious that the substance to be shipped or stored may be introduced into the container through the valves 64, nipples 50 and pipes 60 so as to avoid contact with any material other than the corrosion resistant lining of the container. Obviously contamination of the contents of the container will thus be overcome and any damage to the body of the container 10 by contact with the corrosive substance will be avoided. It is obvious that the contents of the container may be drained by so positioning the container that the eduction pipes 60 extend vertically while the container lies on its side. In the preferred form of the invention both containers 10 and 90 are equipped at opposite ends with bands 142 which extend beyond the convex ends of the container and are provided at their ends remote from the container with inturned flanges 144 which not only serve to protect the heads of the containers but also as handling means by which the containers may be suspended by suitable grappling means. In the preferred form, the bands 142 are provided at spaced intervals with drainage openings 146 to prevent the accumulation of moistures between the heads and the flanges 144.

Obviously the inturned flanges 144 on the bands 142 not only protect the ends of the container but afford level bases upon which the container may rest when in an upright position. They also provide means by which a grab hook or a hold down hook may be connected to the container during loading and transportation. They also serve as means by which skids or shoes may be connected to the container. If so desired the heads 24, 38, 94 and 100 may be provided with bushings 150 having internally screw threaded openings for the reception of plugs 152 which are provided with axial openings containing a substance which will melt when subjected to a temperature which exceeds a predetermined value. It is evident that should sufficient internal pressure be created within either the container 10 or the container 90 the heads 38 or 100 will flex even to the point

of reversing their contour and thus avoid the bursting of the containers.

While in the foregoing there has been shown and described the preferred form of this invention, it is to be understood that minor changes in the details of construction, combination and arrangement of parts may be resorted to without departing from the spirit and scope of the invention as claimed.

I claim:

A container comprising a relatively thin elongated hollow cylindrical body, a relatively thick concavo-convex head carried by and closing each end of said body, one of said heads having a relatively large central opening, a relatively thin auxiliary concavo-convex head closing said opening with its convex side inwardly disposed and forming a valve chamber wholly within the container, said auxiliary head having a discharge port opening through the same, a pipe within the container leading from said port and extending angularly to a point adjacent the junction of said body with the said one head, a valve within the valve chamber and connected with said port to control the discharge of the content of the container from the pipe, circumferentially spaced lugs carried by said auxiliary head and projecting into the

valve chamber, a concavo-convex cover closing said valve chamber with its convex side outwardly disposed and its curvature conforming to that of said one head, and a flange at the periphery of the cover for engagement with the lugs and having spaced notches extending through its periphery for receiving said lugs and to allow said flange to be turned into and out of engagement therewith during the mounting and demounting 10 of the cover on the container.

JAMES R. BARROW.
